DESIGN FOR LACE

Bert Edson, Pawtucket, R. I.

Application February 7, 1936, Serial No. 61,006

Term of patent 3½ years

To all whom it may concern:

Be it known that I, Bert Edson, a citizen of the United States of America, residing in Pawtucket, county of Providence, and State of Rhode Island, have invented a new, original, and ornamental Design for a Lace, of which the following is a specification, reference being had to the accompanying drawing, forming part thereof.

The figure of the drawing is a plan view of a lace embodying my new design.

The design unit is contained between the vertical broken lines, which unit is repeated in regular succession as indicated by the extensions beyond the unit boundaries.

I claim:

The ornamental design for a lace substantially as shown and described.

BERT EDSON.
